Specification of Letters Patent. Patented Dec. 31, 1918.

Application filed February 1, 1918. Serial No. 217,099.

To all whom it may concern:

Be it known that I, SAMUEL R. BELL, a citizen of the United States, and a resident of Beaumont, in the county of Jefferson and 5 State of Texas, have invented certain new and useful Improvements in Refrigerating-Machines, of which the following is a specification.

The invention relates to refrigeration, and 10 one of the main objects thereof is to provide a double jacketed brine cylinder having a self-contained expansion tank for the refrigerant, whereby a relatively great cooling area is provided with a relatively small 15 displacement in the cylinder, and a further object is to provide means for insuring the circulation of the brine through said cylinder.

The invention is fully described in the 20 following specification, of which the accompanying drawings form a part, in which the separate parts are designated by the same reference characters in each of the views, and in which:—

25 Figure 1 is a central, longitudinal, vertical, section taken through a cylinder constructed in accordance with the invention; and

Fig. 2 is a section taken on the line 2—2 30 of Fig. 1.

In the drawings forming a part of this application is shown a present preferred form of embodiment of the invention comprising a cylinder 3 having front and rear heads 4 and 5 supporting a centrally arranged shaft 6 projecting through the former, a suitable stuffing-box 7 being provided therefor, and said shaft will be connected with a suitable source of power, not shown, 40 and carries a plurality of spiral blades 8 secured thereto by means of screws 9, or equivalent, and said cylinder is provided with an inlet pipe 10 adjacent its periphery and with an outlet pipe 11 adjacent its axis.

45 The cylinder head 4 has an inwardly directed flange 12 thereon provided with openings 13 therethrough and, together with the head 5, serving to support two cylindrical sections 14 and 15 spaced apart to form a 50 chamber 16 by means of end rings 17. The chamber 16 serves as a substitute for the conventional refrigerator coil and may be connected with a suitable pump, this not being illustrated, however, as any form thereof 55 may be employed, and said chamber is provided with a pipe 18 at one side, and with

a pipe 19 at the opposite side, both projecting through the wall of the cylinder 3 and suitably packed against leakage into said cylinder, the former of which pipes serves as the expansion pipe and the latter as the suction pipe for the refrigerant, such as anhydrous ammonia or equivalent, admitted to the chamber 16.

The brine or other saline solution enters the outer compartment 20 of the cylinder, through the pipe 10, and fills the same, thus surrounding the chamber 16, and passes thence through the openings 13 to the compartment 21 where it is acted upon by the spiral, rotary, circulator, blades 8 and driven outwardly of the cylinder 3 through the pipe 11; in such passage of the brine a large proportion of the heat therein is absorbed by the refrigerant in the chamber 16 and, after leaving the cylinder 3, may be carried to the air or water coils, ice-pans, or the like and, when its temperature is again raised by its absorption of the heat in the water or air being refrigerated, said brine returns to and is again passed through the cylinder 3.

It will thus be seen that a device is provided through which the saline solution is positively forced for twice the length thereof in the present showing, although one or more additional refrigerant chambers might be provided and the solution passed the length of all, resulting in a very low temperature of said solution; it will also be observed that the unit shown may be duplicated or multiplied in one system in order to exaggerate the result; it will be further noted that each unit comprises the self-contained refrigerant chamber and the brine propulsion means, and that the device, in one or more units, may be placed at any desired point in a refrigerating system.

Reserving the right to all such changes in and modifications of the details of construction shown and described as properly come within the scope of the following claims, what is claimed as new, and desired to secure by Letters Patent, is:—

1. The combination in a refrigerating system, of a cylinder provided with self-contained means for propelling a saline solution therethrough, and with cylindrical members forming a chamber for the refrigerant arranged to cause said solution to traverse said cylinder from end to end in each direction, said chamber having an inlet and an outlet.

2. The combination in a refrigerating system, of a cylinder having an inlet and an outlet, and having a supplemental chamber formed therein, also provided with an inlet and an outlet distinct from said cylinder, a shaft in said cylinder, and spiral blades on said shaft and revoluble therewith to force a saline solution through said cylinder around said chamber, said chamber being adapted for the vaporizing of a refrigerant.

3. As an article of manufacture, a cylinder,

der, a front head, a rear head, an inwardly directed flange on one head, two cylindrical sections spaced apart, rings therebetween for such spacing and forming a chamber distinct from said cylinder, said sections being carried by said flange, an inlet and an outlet for said cylinder, an inlet and an outlet for said chamber, a shaft arranged centrally of said cylinder and projecting therefrom, and spiral blades on said shaft.

SAMUEL R. BELL.
